UNITED STATES PATENT OFFICE.

THOMAS N. MCLEAN, OF ELIZABETH, NEW JERSEY, AND CALVIN B. MCLEAN,
OF STAMFORD, CONNECTICUT.

DEPURATOR.

SPECIFICATION forming part of Letters Patent No. 594,961, dated December 7, 1897.

Application filed December 7, 1896. Serial No. 614,802. (No model.)

To all whom it may concern:

Be it known that we, THOMAS N. MCLEAN, residing at Elizabeth, in the county of Union and State of New Jersey, and CALVIN B. MCLEAN, residing at Stamford, in the county of Fairfield and State of Connecticut, citizens of the United States of America, have invented 55 a certain new and useful Improvement in Apparatus for the Treatment of Diseases, of which the following is a description, reference being had to the accompanying drawings, wherein—

Figure 1 is a view of a person (legs mainly omitted) wearing the apparatus for the practice of said improvement. Fig. 2 is a view of 15 a person (legs mainly omitted) wearing the supporting-frame forming a part of said apparatus. Fig. 3 is a view of said supporting-frame in horizontal cross-section on the plane indicated by the dotted line xx of Fig. 2.

An object and purpose of the improvement (not now undertaking to state all the objects and purposes) is the treatment of disease in 25 the human body by partially removing the atmospheric pressure from a zone of the body comprising the part particularly affected, while permitting other portions of the body to remain exposed to such atmospheric pressure.

30 In the accompanying drawings the letters a and b , respectively, denote two or more corresponding partible sections of what may be termed a "rigid supporting-frame," substantially encompassing the chest and abdomen of 35 the body, leaving a chamber between the body and this supporting-frame. These two sections are partible from each other, the parting being lengthwise. Where the edges meet, they overlap and intermesh, as indicated 40 in Fig. 3. This supporting-frame has what may be termed "shoulder-straps" a' and b' , through the agency of which the shoulders of the person wearing the apparatus support this frame, and there are armholes for the 45 arms just beneath these shoulder-straps.

The letter c denotes perforations respectively located in substantial alinement with the exhaust-tube and indicator-tube, (soon to be described,) which are attached to the outer 50 and upper flexible cover, (soon to be described.)

The letter d denotes a flexible and elastic cover for the upper end and portion of the supporting-frame. By preference it is of sheet-rubber and highly elastic, and by means of 55 this elasticity it automatically makes close contact with the neck and arms of the wearer.

The letter e denotes another flexible and elastic cover for the lower end and portion of the supporting-frame which by its elasticity makes close contact with the legs of the 60 wearer.

The letter f denotes a hoop or ring which may be called a "contact-ring," for the reason that it affords a base or support against 65 which the two overlapping flexible covers bear through atmospheric pressure when air is exhausted from within the chamber.

The letter g denotes an air-pump which may be of any suitable construction, from which 70 an exhaust-tube h runs to connect with the chamber.

The letter i denotes what may be called the "indicator-tube," which may be supplied with a safety-valve and with a gage for indicating 75 the degree of exhaustion within the chamber.

The parts of the apparatus being assembled and in place, as already indicated, then by means of the air-pump and suction-tubes the air is exhausted to a reasonable and desired 80 degree from the chamber which surrounds the body. This operation brings with it valuable curative results, all of which need not be enumerated here. One of these results is to rarefy the air which is in contact with the 85 body, removing to a degree the ordinary atmospheric pressure from the exterior of the body, meanwhile leaving that atmospheric pressure in full effect as regards air which enters the body through the mouth and nose, 90 and also in full effect as regards those portions of the body not inclosed by the chamber.

In the case of lung trouble—for instance, trouble of that nature commonly known as "consumption"—one effect is to expand the 95 lungs beyond that of which the ordinary patient himself is capable and to give the blood in the veins and arteries and capillaries freer course and play than can probably be attained by any other means. Such artificial expansion of the lungs and bronchial tubes opens up their minutest cells for the access thereto 100

of medicated sprays, gases, or vapors introduced by way of the mouth and nose. There are many ways in which this treatment operates beneficially, but this mention of one or 5 two sufficiently indicates them to the trained physician. It affects favorably not only the circulation of the blood, but its aeration, and also the action of all the organs of nutrition. This favorable action includes all the organs 10 and glands which are subjected to the treatment.

We claim as our invention—

In combination, a rigid frame in longitudinal partible sections adapted to form the 15 framework of a chamber substantially en-

compassing the chest and abdomen of the human body, a flexible and elastic overlapping cover adapted to form an air-tight connection with the neck and arms, another flexible and elastic overlapping cover adapted to 20 form an air-tight connection with the legs separately, and a means for partially removing atmospheric pressure from said chamber, all substantially as described and for the purposes set forth.

THOMAS N. MCLEAN.
